UNITED STATES PATENT OFFICE.

CHARLES MARIE ERNEST LOUIS MONNIER, OF VAISON, FRANCE.

SPARKING PLUG FOR INTERNAL-COMBUSTION ENGINES.

1,334,627.

Specification of Letters Patent. Patented Mar. 23, 1920.

Application filed July 29, 1919. Serial No. 814,181.

To all whom it may concern:

Be it known that I, CHARLES MARIE ERNEST LOUIS MONNIER, citizen of the Republic of France, and resident of Vaison, Vaucluse, France, have invented new and useful Improvements in Sparking Plugs for Internal-Combustion Engines, which improvements are fully set forth in the following specification.

10 Sparking plugs for internal combustion engines frequently get out of working order in a very short time which is due partly to the obstruction or fouling of the contacts and partly to the expansion of the central 15 terminal, producing elongation resulting in leakages and heating and consequently in stoppages in working of the plug.

This invention relates to a construction of sparking plug wherein the aforesaid 20 drawbacks are avoided by effecting the ignition of the gaseous mixture by means of a disruptive spark. Moreover the construction of this plug is such as to permit it to be entirely taken to pieces.

25 In the accompanying drawings which illustrate one embodiment of the invention:

Figure 1 is a sectional elevation of the plug.

30 Fig. 2 is a side view of the same.

Figs. 3 and 4 are a sectional elevation and side view of a modification, respectively.

The plug is essentially constituted by a metal body or nipple *a* provided with cooling ribs and in which is mounted an insulator consisting of three parts *b*, *c*, *d*, which are held in position by means of a socket member *e* having an external thread engaging an internal thread in the body *a*. Two 40 thumb nuts *f*, *f'* screwed on the socket *e* lock the latter in position.

A central terminal or electrode comprising two parts *g*, *h* is arranged centrally and longitudinally of the insulator. The lower 45 part *g* is supported in the lower insulator member *b* by a shoulder or collar *j* and the upper part *h* is secured in the upper insulator member *d* by means of a shoulder or collar *l* and the usual arrangement of washers, nut and lock-nut. The internal ends of both parts of the electrode are oppositely arranged in a recess *m* provided in the middle insulator part *c*.

Packing rings of any suitable materials 55 such as aluminium, asbestos, &c., are pro-

vided at *n*, *o*, *p*, *q* in order to secure the desired tightness of the plug.

The upper and lower insulator members *d* and *b* may also be made of any suitable materials such as quartz, mica, porcelain, etc., but the middle insulator member *c* must be made of a transparent material, preferably of quartz.

In operation, a first direct spark is produced between the inner ends of the electrode members in the recess *m*, which forms a bursting chamber. The high frequency current thus produced gives rise to a disruptive spark at the lower end of the electrode member *g*, *i. e.*, in the combustion chamber. On account of the particular features of high frequency alternating currents, this disruptive spark is obtained between the said end of the central terminal and the other terminal, shown in the drawings as being formed by the plug body itself, should even the terminals be fouled.

It will be understood moreover that the expansion of the lower part *g* of the central electrode does not affect the upper part *h* so that the plug is not liable to become loosened or out of order.

A plurality of windows *r* (for instance four in number) are provided in the socket at a level with the bursting chamber *m* so that on account of the transparency of the middle insulator member the spark produced in said chamber may easily be seen. This permits of observing at any moment the correct working of the plugs mounted on an engine and to find easily, without any dismounting, any plug which may not work satisfactorily.

It will be understood that the arrangement herein described may be varied as to details without departing from the spirit of the invention.

Such a modification is shown by way of example in sectional elevation in Fig. 3 and side view in Fig. 4. As shown, the plug body or nipple *a* is modified in such a manner as to permit easy access to the plug in cases where the same is arranged in the hollow valve-covers commonly used in automobile engine construction.

Besides the body *a* is provided internally and concentrically of the socket *e* with an annular chamber *s* communicating with the atmosphere by means of windows *t* provided in the body *a* at a level with the windows *r*

in the socket *e*, on the one hand, and by means of a plurality of holes *u* bored in the socket, on the other hand. Air circulation is thus provided and assists in cooling the plug. Besides these holes may serve to effect the screwing and locking of the socket *e* when mounting the plug.

It will be easily understood that all the members of which the plug is composed may 10 be easily dismounted and remounted.

What I claim is:

1. In a spark plug, the combination of a hollow metal body; a hollow socket mounted in said body and formed with a sight opening which is visible from the outside of the plug; an insulating element composed of upper, intermediate and lower members mounted in superposed relation within said socket, and formed with registering axial 20 passages, the intermediate member being constructed of transparent material and the passages in that member and in the lower member having enlarged portions, the enlargement in the intermediate member being located opposite said sight opening; and an electrode comprising upper and lower axially-alining members mounted in said passages and having supporting shoulders disposed within the enlargements thereof, the 25 confronting ends of the electrode members projecting into the enlargement in the intermediate chamber and spaced from each other therein to provide a spark gap which is visible through said sight opening.
35. 2. In a spark plug, the combination of a hollow metal body formed with an internal annular air chamber and with a plurality of openings extending laterally from said chamber and leading through the outer face 40 of the body; a hollow socket mounted in said base and formed with lateral sight openings which aline with the lateral openings in said body and also formed with vertical openings at its upper end which 45 communicate with said air chamber; an insulating element mounted in said socket and having its central portion located opposite said lateral openings and constructed of

transparent material, said insulating element being formed with an axial passage 50 which opens therethrough at opposite ends; and an electrode comprising upper and lower axially-alining members mounted in said passage, the confronting ends of the electrode members being disposed within 55 the transparent portion of the insulating element at a point opposite said lateral openings so as to be visible through the same.

3. In a spark plug, the combination of a hollow metal body formed with an internal 60 annular air chamber and with a plurality of openings extending laterally from said chamber and leading through the outer face of the body; a hollow socket mounted in said base and formed with lateral sight openings 65 which aline with the lateral openings in said body and also formed with vertical openings at its upper end which communicate with said air chamber; an insulating element composed of upper, intermediate 70 and lower members mounted in superposed relation within said socket and formed with registering axial passages, the intermediate member being constructed of transparent material and the passages in that member 75 and in the lower member having enlarged portions, the enlargement in the intermediate member being located opposite said alining lateral openings; and an electrode comprising upper and lower members 80 mounted in said passages and having supporting shoulders disposed within the enlargements thereof, the confronting ends of the electrode members projecting into the enlargement in the intermediate chamber 85 and spaced from each other therein to provide a spark gap which is visible through said lateral openings.

In testimony whereof I have signed this specification in the presence of two subscribing witnesses.

CHARLES MARIE ERNEST LOUIS MONNIER.
